UNITED STATES PATENT OFFICE.

ALBERT SCHMIDT, OF FLINT, MICHIGAN, ASSIGNOR TO CHAMPION IGNITION COMPANY, OF FLINT, MICHIGAN, A CORPORATION OF MICHIGAN.

SPARK-PLUG.

1,200,532.

Specification of Letters Patent. Patented Oct. 10, 1916.

Application filed July 24, 1913. Serial No. 720,866.

To all whom it may concern:

Be it known that I, ALBERT SCHMIDT, a citizen of the Republic of France, residing at Flint, in the county of Genesee and State 5 of Michigan, have invented certain new and useful Improvements in Spark-Plugs, of which the following is a specification, reference being had therein to the accompanying drawings.

10 The invention relates to spark plugs, and more particularly to the construction of electrodes therefor, and the manner of mounting the same upon the plug casing.

In the drawings: Figure 1 is a bottom 15 plan view of the plug; Fig. 2 is a cross section thereof; and Fig. 3 is an elevation at right angles to Fig. 2, showing the construction and manner of mounting the ground electrode.

20 In the construction of spark plugs, it is usual to mount one electrode upon an insulator core, while the coöperating electrode is grounded upon the metallic casing. This grounded electrode is frequently formed 25 from a piece of wire, one end of which engages an aperture or bore in the end of the casing, while the other end is bent to extend in proximity with the coöperating electrode.

One of the greatest difficulties is the dissipation of heat imparted to this electrode by 30 the contact of the same with the burning gases. In the present invention I have overcome this difficulty by forming the sparking end of the electrode of a lesser cross section 35 than the portion which engages with the outer case, whereby the heat is more rapidly dissipated.

Specifically, A is the metallic casing of 40 the spark plug; B the insulator core therefor; C the electrode mounted upon said core; and D the coöperating electrode which is grounded on the case. In forming the electrode D, a round piece of wire is selected, and is engaged with a bore in the end of 45 the casing in which it is secured by brazing or soldering. The projecting end of this electrode is bent at right angles, as indicated at E, and this bent, laterally-extending portion is fashioned to form a taper 50 from its outer end to the point of engagement with the case. This taper is in a vertical plane and the electrode is so directed as to lie adjacent to the insulated electrode

C, as shown in Fig. 1. I also preferably provide a pair of these grounded electrodes, 55 arranged parallel to each other on opposite sides of the insulated electrode.

In operation, the heat which is imparted to the electrode D from the spark or from contact with the burning gases is conducted 60 through the progressively enlarging cross section into the portion which extends in the bore in the case, and from the latter through the brazed or soldered portion into the main case A. This prevents the over- 65 heating of the outer end of the electrode, and is also a construction which can be easily manufactured at small cost.

What I claim as my invention is:

1. A spark plug, comprising a casing, an 70 insulator core therein, an electrode projecting through said core, and a coöperating electrode, having a shank portion engaging said casing, and a laterally-extending portion of substantially semi-circular cross-section, the cross-sectional area of said laterally-extending portion gradually increasing from the outer end to the shank portion, and an 75 edge of said semi-circular portion being adjacent to the electrode projecting through the core.

2. A spark plug, comprising a casing, an insulator core therein, an electrode projecting through said core, and a coöperating electrode, having a shank portion engaging 80 said casing, and a laterally-extending portion tapering from the shank portion to its free end and provided with a longitudinally-extending edge portion adjacent to the electrode projecting through the core. 90

3. In a spark plug the combination with a casing, of an electrode having a shank portion engaging said casing and a laterally-extending portion tapering in a plane passing through said shank portion and said laterally-extending portion from the shank portion to the free end, a side edge of the laterally-extending portion being adapted to transmit the spark. 95

In testimony whereof I affix my signature 100 in presence of two witnesses.

ALBERT SCHMIDT.
